UNITED STATES PATENT OFFICE.

LOUIS SPRENGER, OF DETROIT, MICHIGAN, ASSIGNOR TO DIAMOND POWER SPECIALTY CO., OF DETROIT, MICHIGAN.

BLOWER FOR BOILERS.

1,026,060.

Specification of Letters Patent. Patented May 14, 1912.

Application filed September 1, 1911. Serial No. 647,170.

To all whom it may concern:

Be it known that I, LOUIS SPRENGER, a citizen of the United States of America, residing at Detroit, in the county of Wayne and State of Michigan, have invented certain new and useful Improvements in Blowers for Boilers, of which the following is a specification, reference being had therein to the accompanying drawings.

10 This invention relates to a boiler blower employed for the purpose of blowing the soot from the tubes of a steam boiler, and it has for one of its objects the provision of a device which comprises a series of superposed 15 nozzles adapted to be projected into and withdrawn from the interior of the boiler setting.

The invention has furthermore for its object the provision of improved means 20 whereby steam under pressure is admitted into said nozzles serially so that one or more of said nozzles may be active at the same time.

Further objects of the invention will hereinafter appear and be particularly defined in the claims.

The invention has been clearly illustrated in the accompanying drawings in which—

Figure 1 represents a fraction of the wall 30 of a boiler setting having my improved blower attached thereto, the blower being shown in its inwardly projected position; and Fig. 2 shows a modification of the device.

35 Referring to the drawings, 10 denotes the side wall of a boiler setting having in its outer face a pocket 11 extending vertically and having a lining 12 to preserve the masonry in proper condition. A series of 40 superposed transverse apertures 13 are provided in the wall 10 adapted to permit the passage of a series of nozzles 14 which are rigidly attached to a pipe or shell 15 provided at points where the nozzles are attached, with annular members 16 which have a close fit with a central tube 17 whereby steam may be admitted to the several nozzles 14 respectively. For this purpose the tube 17 is provided with a series of apertures or 45 ports 18 disposed angularly about the axis of the tube 17 so that the latter must be rotated to bring all of said nozzles into communication with the interior of said tube. The means whereby said tube is rotated in the 50 several seats 16 above referred to, consists

substantially of a head cage 19 having perforations 20 and being rigidly secured to the upper end of the tube 17. The cage is attached to a spindle 21 journaled in the casing 22 and having a suitable steam tight packing 60 to prevent the leakage of steam therethrough. A gear 23 is secured to the upper end of the spindle 21 and is engaged by a similar gear 24 loosely mounted on a stud 25 which is rigidly held in a bracket 26. The 65 latter is stationary upon a pipe 27 which is screwthreaded into the casing 22 above mentioned, and the outer end of which communicates with the interior of a holder 28 having a stuffing box 29 to pack and rotatably support a vertical spindle 30, the axis of which is substantially in parallelism with that of the tube 17 so that the nipple 30 and elbow 28 may constitute a swiveled connection at that point. The lower end of the tube 17 may 70 rest upon a plug 31 secured in the shell 15 and bifurcated to receive between the branches thereof a roller or wheel 32 adapted to run upon the lining base plate 12' of the boiler setting. The nipple 30 communicates 75 with a horizontal pipe 33 which in turn communicates through a swiveled elbow 34 with a leader 35 which receives high pressure steam from any convenient source.

From the foregoing description, it will be 80 understood that the tube 17 together with its inclosed shell 15 will remain in vertical position, that furthermore, by virtue of the swivel connections 28 and 34, said shell 15 may be moved to bring the nozzles 14 into the 85 inwardly projecting position shown in Fig. 1, and that furthermore the shell and the nozzles may be withdrawn from the interior of the setting when not in use.

Under ordinary circumstances the steam 90 leader 35 is disposed at considerable height above the floor of the boiler room, and, in order to bring the mechanism whereby the tube 17 is rotated, within easy reach of the operator, I preferably mount a sprocket 95 100 upon the hub of the bevel gear 24, this sprocket being connected by a chain 37 with a similar sprocket 38 loosely mounted upon a fixed stud 39 which may be attached to the shell 15 in any desired manner. The hub 105 of the sprocket 38 carries a hand wheel 40, the web of which is provided with a spring pressed plunger 41 adapted to engage a series of depressions 42 formed in a disk 43 which is rigidly attached to the stud 39, the 110

depressions being so spaced as to engage the stud in certain predetermined positions of the ports of the tube 17 so that the operator may be enabled, not only to ascertain which 5 ports of the tube 17 are active but also to be sure that the ports are in full register with the respective nozzles pertaining thereto.

In Fig. 2 I have illustrated a modification of the tube operating mechanism, the 10 distributing tube 17^a extending, in this instance, to a considerable distance above the floor as for example, in vertical boilers, and the operating mechanism as here shown in a position intermediate the extreme end of the tube 17^a which is provided with a bevel gear 23^a in engagement with a similar gear 24^a. The latter gear is secured to a spindle 45 journaled in a plug sleeve 46 which is provided with a stuffing box 47. The spindle 45 also carries a hand wheel 48 provided with a spring pressed plunger 49 which is adapted to engage suitable depressions formed in the front face of a casing 50, the interior of which is chambered to form a 25 steam chamber 51 which is in constant communication with the interior of the tube 17^a through an aperture 52. Extending vertically and at opposite sides from the casing 50, are the tube supporting shells 53, 54 30 provided with annular seats 16^a as previously described in connection with Fig. 1. Likewise the nozzles like those shown at 14 may be employed as before. Steam is admitted into the casing or chamber 51 35 through the nipple 30 which corresponds to that shown in Fig. 1 and which is also connected with the leader 35 as before stated. From the foregoing it will be seen that the mechanism for operating the tube 17^a is in 40 this instance direct in contradistinction to the sprocket-and-chain mechanism previously described.

Many changes may be made in the construction and organization of some of the 45 elements of my improved device without departing from the spirit of the invention.

I claim:

1. The combination with a steam-supply pipe, of a shell, nozzles secured to said shell 50 and projecting thereinto, a ported tube rotatable in the shell, means for rotating said tube to bring its ports into register with the nozzles respectively, and means for supporting said shell for bodily swinging movement 55 on the supply pipe to move said nozzles simultaneously and equally.

2. The combination with a steam-supply pipe, of a shell connected therewith and having stationary ported annular seats, nozzles secured to said shell and projecting into 60 said seats, a ported tube rotatable in the shell, and means for rotating said tube to

bring its ports into register with the nozzles respectively.

3. The combination with a vertical steam-supply, a horizontal leader swiveled thereon, a vertical nipple on said leader, and a casing swiveled on said nipple for movement in a horizontal plane, of a vertical shell secured to said casing, nozzles communicating 70 with the interior of said shell, a valve tube having unalined ports adapted to register with the nozzles, and means for rotating said tube.

4. The combination with a vertical steam-supply, a horizontal leader swiveled thereon, a vertical nipple on said leader, and a casing swiveled on said nipple for movement in a horizontal plane, of a vertical shell secured to said casing, nozzles communicat- 75 ing with the interior of said shell, a valve tube having unalined ports adapted to reg- 80 ister with the nozzles, a spindle passing through said casing and secured to said tube, and means for rotating said spindle. 85

5. The combination with a vertical steam-supply, a horizontal leader swiveled thereon, a vertical nipple on said leader, and a casing horizontally swiveled on said nipple, of a vertical shell secured to said casing, noz- 90 zles communicating with the interior of said shell, a valve tube having unalined ports adapted to register with the nozzles, a spin- 95 dle passing through said casing and secured to said tube, a hand-wheel, and means for connecting said spindle and hand-wheel for rotating said spindle.

6. The combination with a steam-supply pipe, of a shell connected therewith, nozzles secured to said shell and projecting thereinto, a ported tube rotatable in the shell, and means intermediate the ends of the tube and the outermost nozzles thereof for rotat- 100 ing said tube to bring its ports into register with the nozzles respectively, said means comprising a hand-wheel and gear connection therefor. 105

7. The combination with a vertical steam-supply, a horizontal leader swiveled thereon, a vertical nipple on said leader, and a 110 casing swiveled on said nipple, of a vertical shell secured to said casing horizontally, nozzles communicating with the interior of said shell, a valve tube having unalined ports adapted to register with the nozzles, a spin- 115 dle passing through said casing and secured to said tube in axial alignment therewith, and means for rotating said spindle.

In testimony whereof I affix my signature in presence of two witnesses.

LOUIS SPRENGER.
